Primary Examiner — John R Yeh(74) *Attorney, Agent, or Firm* — Xiaofang Zhong(57) **CLAIM**

The ornamental design for a bag, as shown and described.

DESCRIPTION

FIG. 1 is a front, right, and top perspective view showing my new design for a bag in an opened configuration;
 FIG. 2 is a front, left, and top perspective view thereof;
 FIG. 3 is a front elevation view thereof;
 FIG. 4 is a rear elevation view thereof;
 FIG. 5 is a right elevation view thereof;
 FIG. 6 is a left elevation view thereof;
 FIG. 7 is a top plan view thereof;
 FIG. 8 is a bottom plan view thereof;
 FIG. 9 is a front, right, and top perspective showing my new design for a bag in closed configuration;
 FIG. 10 is a front, left, and top perspective view thereof;
 FIG. 11 is a front elevation view thereof;
 FIG. 12 is a rear elevation view thereof;
 FIG. 13 is a right elevation view thereof;
 FIG. 14 is a left elevation view thereof;
 FIG. 15 is a top plan view thereof;
 FIG. 16 is a bottom plan view thereof;
 FIG. 17 is an enlarged view of a portion labeled as 17 on FIG. 1;
 FIG. 18 is an enlarged view of a portion labeled as 18 on FIG. 1; and,
 FIG. 19 is an enlarged view of a portion labeled as 19 on FIG. 2.

The dot-dash broken lines illustrate the enlargement indications and form no part of the claimed design.

1 Claim, 19 Drawing Sheets(56)
